UNITED STATES PATENT OFFICE.

ANGELO PETIX, OF NEW YORK, N. Y.

GAS-COCK AND THE LIKE.

1,253,093.

Specification of Letters Patent.

Patented Jan. 8, 1918.

Application filed December 3, 1915. Serial No. 64,833.

To all whom it may concern:

Be it known that I, ANGELO PETIX, subject of the King of Italy, residing at New York, in the county of New York and State 5 of New York, have invented certain new and useful Improvements in Gas-Cocks and the like, of which the following is a specification.

This invention relates to gas cocks and 10 the like and has as its object to provide means for locking such cocks in their closed position in order to prevent their being accidentally opened, as is often the case especially in gas stoves and ranges, where an 15 animal jumping on the handle or key of the cock, or a piece of garment brushing by, or a child playing with the cock may open it, precipitating accidents or, in the best case, causing a waste of gas.

20 With the foregoing and other objects in view, the invention consists in the particular construction, arrangement and combination of parts, more specifically described hereinafter and shown in the accompanying 25 drawing, in which: —

Figure 1 is a vertical section of a gas cock such as ordinarily used for stoves and kitchen ranges, provided with my device;

Fig. 2 a partly sectional, partly elevational view thereof, the section being taken on line 2—2 of Fig. 1;

Fig. 3 a similar view, the section being taken on line 3—3 of Fig. 1, and some parts being broken away.

35 Referring more particularly to the drawing, in which like reference characters are applied to similar parts throughout the several views, 7 is a gas cock such as is ordinarily used on gas stoves and ranges. A cavity is formed in the plug 9 of the cock. Pivoted on a pin 10, a lever 11 is mounted in the cavity 8 and is normally held in the position indicated in full lines in Fig. 1, by a plate spring 12 secured to it at its lower 45 end. A lug 13 is also carried by the lower end of the lever 11 and projects, through a hole 14 made in the plug 9, into a recess 15 formed in the socket 16. This locks the plug in the socket in the closed position of the cock, shown in Fig. 1, and a similar recess formed at a quarter turn distance from the recess 15, in the socket, when engaged by the lug 13 would lock the cock in its open 50 position.

A rod 17 passes through the hollow handle 18 of the cock 7, its inner end, projecting into the cavity 8, being enlarged as at 19 to prevent its being withdrawn and abutting against the upper end of the lever 11. A knob 20 is mounted on the outer end of 60 the rod 17, normally a slight distance away from the end of the handle 18, as shown in full lines in Fig. 1, but susceptible of being pressed into contact therewith, as indicated in dotted lines, whereupon the lever 11 will 65 be tilted on its pivot and withdraw the lug 13 from engagement with the recess 15, all as shown in dotted lines in Fig. 1.

It will be understood that while I have thus shown and described the preferred 70 forms of embodiment of my invention, I do not want to be limited to its mechanical details and may resort to such modifications and alterations as come within the scope of the claims hereunto appended. Also that I 75 may use my device in conjunction with other than gas cocks, such as for instance faucets for valuable liquids, where my device may be used with advantage to prevent waste by an accidental opening of the faucet.

I claim:

1. A cock or faucet comprising, in combination, a socket, a plug rotatably mounted therein, means adapted to lock said plug in said socket from rotation, a handle operatively connected to said plug, at right angles thereto, a push-rod slidably mounted in said handle and a lever pivotally mounted in said plug, adapted to be engaged by said push rod and to operate said locking means, substantially as and for the purpose set forth.

2. A cock or faucet comprising, in combination, a socket, a plug rotatably mounted therein, means adapted to lock said plug in 95 said socket from rotation, a handle operatively connected to said plug, at right angles thereto, a push-rod slidably mounted in said handle and a lever pivotally mounted in said plug, adapted to be operated by said 100 push-rod and to operate said locking means.

In testimony whereof, I affix my signature in the presence of two witnesses.

ANGELO PETIX.

Witnesses:

A. HAMBURGER,
F. D. BABCOCK.
